FEED MECHANISM

Application filed April 17, 1929. Serial No. 355,848.

This invention relates to feed mechanisms and comprises all the features of novelty herein disclosed in connection with cross feed mechanism for a grinding machine. An object of the invention is to provide improved feed mechanism whereby both coarse and fine feeds may be obtained in sequence. Another object is to provide improved mechanism for reversing the feed, especially of a grinding wheel or a work head, in order to prevent marking the work at the conclusion of grinding and to position the wheel and the work for a new grinding operation. Another object is to provide improved back off mechanism for facilitating the repetition of a cut without damage to the work and with minimum attention by the operator. Another object is to provide improved feed mechanism which accurately compensates for wear of a cutting tool. To these ends and to improve generally and in detail upon devices of this general character, the invention further consists in the various matters hereinafter described and claimed.

In its broader aspects the invention is not necessarily limited to the specific embodiment selected for illustrative purposes in the accompanying drawings in which

Fig. 1 is a front view of the device with some parts in section.

Fig. 2 is a plan view.

Fig. 3 is a side view with some parts in vertical section and some broken away.

Fig. 4 is a front view of one form of cutting machine to which the invention is applicable.

Fig. 5 is a front view of a modified construction.

Fig. 6 is a front view of certain details thereof.

Fig. 7 is a side view of parts shown in Fig. 5.

Fig. 8 is a perspective view of a detail.

The invention is especially applicable to cutting machines such as internal grinding machines having a longitudinally reciprocating table 6 carrying a cross feed slide 8 for the grinding wheel 10. Any suitable work head may be mounted on the bride 11. The numeral 12 indicates a screw stud for fastening to the cross slide 8 and having a split nut 14

engaging the threads 16 of a feed shaft 18 which can be turned, either by a hand wheel 20, whose hub 22 is keyed to the shaft and held by a nut 24, or by pawl and ratchet mechanism. An actuating arm having a hub 26 is 55 rockably mounted on the hub 22 and on an extension 28 of a ratchet wheel 30 keyed to the shaft. A bushing 32 is held on the shaft by a sleeve 34 which is secured to the shaft by a taper pin 36. Rotatable on the bushing 60 is a sleeve 38 having a flange 40 entering a recess in wheel 30 and secured by screws to a flange 42 on a ratchet wheel 44. The sleeve 38 is exteriorly threaded, in a direction opposite to that of the screw threads 16 and 65 engages cooperating threads on a nut 46 seated in an annular projection 48 of a bracket 50 which is attachable to the longitudinally reciprocating table to slide therewith. The nut is secured to the bracket by screws 52 70 passing through a flange 54 and the threads are lubricated from an oil cup 56 leading to registering ducts 58 in bracket and nut. These threads may have the same pitch as the 75 threads 16 or may be coarser.

A spiral spring 60 is fastened at one end by a screw to the outside of the projection 48 and is fastened at the other end by a headed pin 64 to the ratchet wheel 44 whose rim overlaps a circular face 66 of the bracket 50 to form a housing. Access to the screw is provided by an opening 68 having a detachable cover plate 70. The spring is wound up by ratchet mechanism during the feeding and is entirely housed with provision for some axial displacement of its convolutions when the ratchet wheel 44 is released and backed away from the bracket 50 by the spring. As will appear, turning of the ratchet wheel 44 and its nut 38 will cause bodily movement of the feed shaft axially and so advance the nut 14 and its cross slide bodily. When the ratchet wheel 30 is turned too, there is an additional movement of the nut 14 and cross slide because of the feed shaft threads 16 rotating in the nut. Both actions occur initially for a coarse feed and later only one for a fine feed. A ring 72, set in a recess of the ratchet wheel 30, carries a plurality of spring fingers 74 bearing against the flange 42 to hold the 95 100

wheels 30 and 44 together frictionally for simultaneous rotation while allowing subsequent rotation of one wheel independently. Wheel 30 carries a felt dust ring 76 engaging wheel 44.

The rim of wheel 44 is provided with two series of teeth 78 and 80 divided by a groove 82 in which a ring 84 can be rotatably adjusted and held by a set screw 86 (Fig. 1). The ring 10 may be split at one point and the sections joined by a plate 88 having fastening screws 90. A lateral projection or shield 92 extends over the series of teeth 78 and has inclined ends or cams 94 to lift a pair of pawls as will appear. The ratchet wheel 30 has a bevelled surface 96 which may be provided with a scale numbered in accordance with teeth 98 on its periphery. There are two pawls 100 for each series of teeth 98 and 78, one pawl of 20 each pair being set half a tooth ahead of the other so that coarser teeth may be employed for a better grip without increasing the minimum possible feed stroke of the ratchet wheel. Twin pawls are not essential however. The pawls are secured to pawl levers 102 spaced apart by washers 104 and pivoted on a shouldered stud 106 which is secured by a nut 108 to a swinging arm 110 carried by the hub 26. The pawl levers have short arms 30 112 arranged to engage adjustable lifting screws 114 (one for each pair of pawl levers) threaded in an arm 116 projecting from the bracket 50. An adjusting stop screw 117 is also threaded in arm 116 to engage the swinging arm 110 to limit the downward movement of the arm and so adjust the beginning and amplitude of its stroke. A stud 118 is secured by a nut 120 to the end of the swinging arm 110 and projects rearwardly past the 40 hubs of the pawl levers. Leaf springs 122, one for each pawl, press the pawls towards the ratchet wheels and are all secured to the stud 118 by a clamp plate 124. The end of the stud 118 carries a shouldered screw 126 with a bushing 128 rotatably supporting a cam roller 130 which intermittently engages a cam 132 on a cam plate 134 adjustably fastened by a set screw 135 to a rock rod 136. The roller rides up the cam and swings the 50 arm 118 when the reciprocating table, which carries the feed mechanisms, moves to the left in Fig. 1. When the roller rides down the cam, each pawl arm 112 may engage its screw 114 and be lifted from the ratchet wheel, while the swinging arm 110 is arrested by its screw 117. The stroke of the arm 110 is adjusted by the screw 117 and the beginning of the stroke of the two pairs of pawls can be varied by independent adjustment of their 60 screws 114. In other words, the screws 114 can be set so that they will let the respective pairs of pawls swing towards the ratchet wheels at different times to skip more or less ratchet teeth as the swinging arm is lifted by the cam.

The rock rod 136 is journaled in lugs 138 on the bracket 50 and is pinned at one end to a collar 140 having a stud 142 connected by a coil spring 144 to a stud 146 on a housing 148 secured by screws 150 to the frame of the machine, a locating tongue 152 on the housing entering a slot in the frame. The spring normally holds the cam 132 in the path of the roller 130 but the cam plate can be rocked forwardly to get it out of the path of the roller when it is desired to stop feeding as when the work reaches size. The collar 140 is pinned to a shaft 154 journaled in the housing 148 and having a squared portion carrying an arm 156 with a core pin 158 entering the core of a solenoid 160. The solenoid may be energized in any suitable way as by the control of a feeler gauge which rides on the work. Thus the solenoid will attract the core pin and rock the shaft to move the cam out of the path of the roller. The same rocking movement of the shaft is made to initiate a reverse feed or back off device operated by the spiral spring 60.

As the ratchet wheel 44 is turned by the pawls, the spiral spring 60 becomes tensioned but the ratchet wheel is locked against reverse movement by a pair of pawls 162 (like pawls 100) engaging the set of teeth 80. The pawls are carried by latch levers 164 pivoted at 165 to the bracket 50 and pressed to locking position by coil springs 166 set in recesses of a lug 167. An adjusting screw 168 engages both levers while carried by one end of a trip lever 170, pivoted at 171 on the bracket 50 and having an adjusting screw 172 engaging a rock arm 174 operating through a notch 176 in the bracket 50 and secured by a key 178 to the rock shaft 136 between lugs 138. The rock shaft has a long keyway 179 so that the arm can be rocked by the shaft in different longitudinal positions of the bracket 50 with which the arm shifts longitudinally of the main frame. Thus, when the shaft is rocked at the conclusion of grinding, the pawls 162 are tripped and the coil spring turns the wheel 44 backwardly until a stop plate 180 on the rim of wheel 44 engages a plunger 182 backed up by a resilient bumper 184 in a bore of a boss 186. This back off does not occur of course until after the shield 92 lifts the rear pair of feed pawls 100 and until after the ratchet wheel 30 has had its turning movement independently of the ratchet wheel 44. When the rear pawls 100 are raised, the wheel 44 stops turning but the wheel 30 can thereafter turn alone because the springs 74 allow slip and are not strong enough to transfer any further turning movement to the wheel 44 against the tension of the spiral spring 60. To insure release of the locking pawls when the table retreats to remote position after grinding, a cam 188 on a bracket 190 is arranged in the path of the pawl levers 164. The bracket 50 is bolted to

the reciprocating table or carrier by bolts 192 and its sides having inclined ways 194 which form extensions of the ways cut in the table for the cross slide.

In operation, reciprocation of the cross feed mechanism with the table causes the cam roller 130 to engage the cam 132 thereby actuating the pawls 100, the rear pair of pawls, which are preferably set for a coarse feed, turning the ratchet wheel 44 and causing an axial bodily shifting of the feed shaft and nut 14. The ratchet wheel 30 is simultaneously turned at the same speed because the spring fingers 74 hold the ratchet wheels together and thus the screw threads 16 advance the nut 14 to a further extent. When the previously set shield 92 reaches the rear pair of pawls and lifts them from the ratchet, the ratchet wheel 44 stops feeding with the spiral spring 60 under tension, but the front pair of pawls, which are set for a fine feed, advance the ratchet wheel 30 slowly and cause a slow advance of the nut 14 by the screw threads 16, the axial shifting of the feed shaft 16 having ceased. When the finished size of the work is reached, as determined by any suitable feeler gauge which controls an electric circuit, the solenoid 160 is energized to rock the shaft 136. The cam 132 is moved out of the path of the roller 130 to stop the fine feed and the locking pawls 162 are tripped. The ratchet wheel 44 is turned backwardly to its original position by the spiral spring, the stop plate 180 and plunger 182 yieldingly stopping the wheel. The ratchet wheel 30 is likewise turned backwardly because of the spring fingers 74 holding the two wheels together. Thus the feed shaft 18 is moved back bodily endwise to its original longitudinal position while the screw threads 16 are turned back to bring the nut 14 back towards but not quite to the original position, the difference from the original position being only that corresponding to the small amount of independent turning of the feed shaft by the fine feed pawls. This action effects an accurate, progressive and automatic compensation for wear of the grinding wheel as will be evident from the following considerations. When grinding, internally or externally, a series of work-pieces to the same size, the cutting edge of the wheel should always advance to the same point which point is at a constant distance from some point of reference on the machine, such as the center of the work or the work holder, and the grinding always ceases and back off occurs at this instant under control of the gauge. The amount of back off depends on the setting of the shield 92 and is determined by the quantity of stock to be removed plus some additional amount for safety so that the grinding wheel will clear a subsequent unground work-piece. A subsequent coarse feed advance of the nut 14 by the simul-

taneous rotation of the two ratchet wheels must be precisely equal to the amount of back off but additional wear occurs meanwhile on the grinding wheel so that the cutting edge does not advance quite so far as the nut. Hence, the subsequent slow speed advance of the nut by the independent rotation of the one ratchet wheel 30 takes care of the remaining stock to be removed and makes up for wear on the grinding wheel, and any reduction in size due to dressing, the gauge again stopping the grinding wheel when its cutting edge is at the same point as before.

Figs. 5, 6, 7 and 8 illustrate a modification of the trip mechanism which enables a shorter rock shaft to be used and otherwise simplifies the mechanism. The lever 170 having the headed screw 168 which trips the pawl levers 164 has a long arm 200 offset forwardly a little and carrying a pin 202 arranged under a movable cam plate 204 which is elongated in the direction of the length of the arm. The cam plate has a cupped enlargement 206 secured by a pin 208 to the end of a rock shaft 210. Spaced ears 212 and 214 on the plate form a slot to receive a nut 216 threaded on a stud 218 adjustable vertically in aligned bores of the ears. A cam 220 at the upper end of the stud is arranged to operate the roller 130 of the ratchet feed mechanism and is adjustable vertically by the nut to vary the throw of the roller. The lower end of the stud 218 is reduced in size and slotted as at 222 to receive a pin 224 which prevents rotation of the stud. The cam 220 is inclined downwardly towards the roller and is also convexly rounded a little on the top. The cam plate 204 also has an inclined face 226 at the end towards the pin 202 so that if the cam plate is depressed when the pin is beyond it, the pin will be cammed downwardly on the next inward stroke of the table carrying the cross feed mechanism.

The rock shaft 210 is journalled in lugs 228 of a bracket 230 which is fastened by clamping bolts 231 on the machine frame, collars 232 secured to the shaft engaging the lugs for preventing axial movement of the shaft. A forked arm 234 is keyed to the shaft and pivotally connected by a rod 236 to a forked arm 238 pinned on a shaft 240 which is journalled in a housing 242 which encloses a solenoid. Pinned to the shaft inside the housing is a bent arm 244 having a core 246 to enter the windings of a solenoid 248 which is pressed against the rear wall of the housing by leaf springs 250. A spring pressed headed plunger 252 is carried in the core in position to engage a surface 254 on the housing. The plunger acts as a buffer when the solenoid attracts the core to rock the shaft 210 and operate the trip lever arm 200 and also initiates return movement when the sole-

noid is de-energized. An adjustable stop screw 256 is threaded in the housing cover to engage the bent arm 244 and so locate the cam plate 204 in proper relation to the roller 130 and trip lever arm 200.

We claim:

1. In a cross feeding mechanism, a shaft having threads, a shiftable nut engaging the threads, a threaded sleeve rotatably journaled on the shaft, a bracket, a nut fixed to the bracket and threaded on the sleeve, means for simultaneously turning the rotary sleeve and the shaft to produce a coarse feed of the shiftable nut, and means for turning the shaft independently of the rotary sleeve for producing a fine feed of the shiftable nut; substantially as described. 70
2. In a cross feeding mechanism, a shaft having threads, a shiftable nut engaging the threads, a threaded sleeve rotatably journaled on the shaft and held from axial movement with respect to the shaft, a bracket, a nut fixed to the bracket and threaded on the sleeve, means for turning the sleeve to produce bodily shifting of the shaft and its nut, means for stopping the turning movement, and means for thereafter turning the shaft at slow speed to produce a fine feed of the shiftable nut; substantially as described. 75
3. In a cross feeding mechanism, a shaft having threads, a shiftable nut engaging the threads, a threaded sleeve rotatably journaled on the shaft, a bracket, a nut fixed to the bracket and threaded on the rotary sleeve, ratchet mechanism for simultaneously turning the sleeve and the shaft to produce a coarse feed of the movable nut, ratchet mechanism for turning the shaft independently of the sleeve to produce a fine feed of the movable nut, and a spring, tensioned during feed, for producing reverse movement of the sleeve and shaft; substantially as described. 80
4. In a cross feeding mechanism, a shaft having threads, a shiftable nut engaging the threads, a threaded sleeve rotatably journaled on the shaft, a bracket, a nut fixed to the bracket and threaded on the sleeve, means turning the rotary sleeve and the shaft to produce a coarse feed of the movable nut, and a spring tensioned by the turning of the rotary sleeve for reversing the sleeve; substantially as described. 85
5. In a cross feeding mechanism, a shaft, a threaded sleeve rotatably journaled on the shaft, a bracket, a nut fixed to the bracket and threaded on the sleeve, means for turning the rotary sleeve to cause a bodily shifting of the shaft, and a spring having connections with the bracket and the rotary sleeve for reversing the sleeve and retracting the shaft; substantially as described. 90
6. In a cross feeding mechanism, a shaft, a threaded sleeve rotatably journaled in the shaft and held against axial movement with respect to the shaft, a bracket, a nut fixed to

the bracket and threaded on the sleeve, a ratchet wheel connected to the sleeve, a spring connected to the wheel and to the bracket, means for turning the wheel and sleeve to tension the spring and shift the shaft, a pawl for locking the wheel with the spring under tension, and tripping mechanism for the pawl to allow the spring to reverse the wheel and sleeve to retract the shaft; substantially as described. 95

7. In a cross feeding mechanism, a shaft having threads, a shiftable nut engaging the threads, a threaded sleeve rotatably journaled on the shaft, a bracket, a nut fixed to the bracket and threaded on the sleeve, a ratchet wheel carried by the sleeve, a ratchet wheel carried by the shaft, a spring between the wheels, a coarse feed pawl for turning both wheels together, a fine feed pawl for turning one of the wheels alone, and means for reversing both of the wheels; substantially as described. 100

8. In a cross feeding mechanism, a feed shaft, means comprising a movable arm for actuating the shaft, a reciprocating carrier for the shaft and the arm, a rock shaft having a cam in the path of the arm to cause actuation of the arm when the carrier reciprocates, and means for rocking the rock shaft to move the cam out of the path of the arm to stop the arm actuation; substantially as described. 105

9. In a cross feeding mechanism, a feed shaft, means comprising a movable arm for actuating the feed shaft in one direction for feeding a reciprocating carrier for the shaft and the arm, mechanism for reversing the movement of the feed shaft, a rock shaft having a cam in the path of the arm to cause actuation of the arm when the carrier reciprocates, and means for rocking the rock shaft to move the cam out of the path of the arm for stopping the feed and rendering the reversing mechanism effective; substantially as described. 110

10. In a cross feeding mechanism, a feed shaft, means for actuating the feed shaft in one direction for feeding, mechanism for reversing the movement of the feed shaft, locking means for the reversing mechanism, a rock shaft, electrically operated means for rocking the shaft, and means carried by the rock shaft for effecting a stopping of the feed and a release of the locking means for rendering the reversing mechanism effective; substantially as described. 115

11. In a cross feeding mechanism, a feed shaft, means for actuating the feed shaft in one direction for feeding, mechanism for reversing the movement of the feed shaft, a latch for locking the reversing mechanism, a tripping lever for the latch, a reciprocating carrier for said parts, a frame supporting said carrier, a rock shaft rockably mounted on the frame, and an elongated plate carried

by the rock shaft for actuating the tripping lever in different positions thereof; substantially as described.

12. In a cross feeding mechanism, a feed shaft, pawl and ratchet mechanism for actuating the feed shaft in one direction for feeding, a rock shaft having a cam for actuating the pawl and ratchet mechanism, and means for rocking the rock shaft to move the cam out of operative relation to the pawl and ratchet mechanism; substantially as described.

13. In a cross feeding mechanism, a member to be fed, a plurality of feeding devices operable simultaneously for imparting a coarse feed to the member, means for subsequently operating one of the feeding devices independently of the other to impart a fine feed to the member, and means for causing simultaneous reverse movement of both feeding devices to the extent of their coarse feed advance; substantially as described.

14. In a compensating cross feeding mechanism, a tool having a cutting surface to be fed repeatedly to a definite point to reduce a plurality of work-pieces successively to the same size, a plurality of feeding devices operable simultaneously for imparting a coarse feed advance to the tool, means for subsequently operating one of the feeding devices independently of the other to impart a wear compensating feed to the tool sufficient to bring its worn cutting surface to said definite point, and means for causing simultaneous reverse movement of both feeding devices to the extent of the coarse feed advance; substantially as described.

15. In a cross feeding mechanism, a feed shaft, means comprising a movable arm for actuating the feed shaft in one direction for feeding, a reciprocating carrier for the shaft and the arm, mechanism for reversing the movement of the feed shaft, locking means for the reversing mechanism, a rock shaft having a cam in the path of the movable arm to cause actuation of the arm when the carrier reciprocates, means for rocking the rock shaft to move the cam out of the path of the arm for stopping the feed, and mechanism actuated by the rock shaft for releasing said locking means and thereby rendering the reversing mechanism effective; substantially as described.

16. In a cross feeding mechanism, a member to be fed, a pair of ratchet wheels operable simultaneously for imparting a coarse feed to the member, means for subsequently operating one of the ratchet wheels independently of the other to impart a fine feed to the member, and mechanism for automatically causing a definite reverse rotation of at least one of the ratchet wheels to retract the member; substantially as described.

17. In a cross feeding mechanism, a member to be fed, a pair of ratchet wheels, means

for rotating both ratchet wheels simultaneously, means for rotating one of said ratchet wheels independently of the other, a feed shaft connected to one of said ratchet wheels and having driving connection with the member to be fed, and means for causing said rotation of said other ratchet wheel to effect an axial movement thereof with the shaft; substantially as described.

In testimony whereof we hereunto affix our signatures.

JAMES F. WILLIAMS.
